RELAY

William W. Eitel and Jack A. McCullough, San Bruno, Calif., assignors to Eitel-McCullough, Inc., San Bruno, Calif., a corporation of California

Application February 11, 1942, Serial No. 430,388

7 Claims. (Cl. 200—87)

Our invention relates to a vacuum relay in which the relay parts are enclosed within an evacuated envelope.

It is among the objects of our invention to provide an improved construction and arrangement of relay parts within the envelope.

Another object is to provide an improved armature and mounting therefor.

A further object is to provide an improved magnetizable core within the envelope for controlling the armature.

The invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawing:

Figure 1 is a longitudinal vertical sectional view of a relay embodying the improvements of our invention, taken in a plane indicated by line 1—1 of Figure 2; and

Figure 2 is a transverse vertical sectional view of the same, taken in a plane indicated by line 2—2 of Figure 1.

Figure 3 is an exploded view of the armature.

In terms of broad inclusion, our improved relay comprises an envelope having a pair of aligned branches and a third branch angularly disposed thereto, and a three-part relay mechanism arranged in the envelope. Each part of the mechanism terminates in a lead, one of the leads being sealed in each of the envelope branches. One of the relay parts includes a core and another part includes an armature. Means external to the envelope are also provided for magnetizing the core to control the armature. Improvements are further provided in the construction and arrangement of the core and armature.

In greater detail, and referring to the drawing, our vacuum relay comprises an evacuated envelope of suitable material, such as glass, having coaxial tubular branches 2 and 3 and a third tubular branch 4 disposed at substantially right angles thereto. Branches 2 and 4 are of substantially equal length, and branch 3 is quite short compared to the others, thus providing an L-shaped body. The envelope is evacuated through a suitable tubulation which is sealed off at point 6.

The relay mechanism comprises three parts, each terminating in a lead sealed in a separate branch of the envelope. A pair of these leads 7

and 8 are aligned and project into the envelope through the ends of branches 2 and 3 respectively. They are sealed to the glass by seals 9 and 11 formed at the ends of the tubular branches. The inner ends of these leads provide contact points and are spaced apart and lie on opposite sides of the axis of branch 4. The third lead 12 projects into the envelope from the end of branch 4, through a seal 13. These various leads are of a suitable metal, preferably tungsten.

The armature part of the relay mechanism is connected to lead 12, and comprises a pair of soft iron plates 14 and 16 disposed between the aligned leads. Armature plate 14 is longer than the other and is secured to a pair of resilient arms 17 of say tungsten. The lower ends of arms 17 are held by a suitable bracket 18 formed to embrace the arms and lead 12; and the upper ends of the arms are welded to a strap 19 which in turn is welded to plate 14. A pair of tungsten contacts 21 are arranged in apertures 22 in armature plates 14 and 16 for contacting the ends of aligned leads 7 and 8. It is difficult to weld tungsten directly to iron, so we weld the contacts to opposite faces of a thin sheet 23 of nickel, which in turn is welded between the iron plates of the armature.

Arms 17 of the mounting structure are sufficiently flexible to allow movement of the armature between the aligned leads, and the arms are disposed to normally hold the armature engaged with lead 8. Figure 1 shows the arms slightly stressed to provide the desired bearing pressure.

The core part of the relay mechanism is an elongated cylinder 24 of magnetizable material, preferably soft iron, disposed about lead 7 in branch 2 of the envelope, with an end of the core terminating close to the inner end of lead 7 near the armature plate 14. This core is magnetized by an external coil 25 disposed about envelope branch 2, so as to control the armature. Thus, when coil 25 is energized, the armature is attracted by the magnetized core to break contact with lead 8 and establish contact with lead 7. When the coil is deenergized the resiliency of arms 17 causes the armature to reengage lead 8.

As best shown in Figure 1, core 24 is connected to lead 7 at the core end remote from seal 9, the remaining portions of the core being spaced from the lead by a bore 26 of larger diameter than the lead and extending into the core from the end nearest seal 9. Connection between the core and lead is preferably made by press fitting the lead in a hole at the end of the core, allowing the lead to project a slight distance be-

yond the end face of the core for engaging the armature contact.

By the above described construction the core is spaced from the lead for the major portion of the core length, and heat generated in the core must travel back along the length of lead 7 before reaching seal 9 by conduction. This tends to thermally isolate the seal from the core, and prevents the glass at the seal from cracking.

Another important feature is that the hollow core construction facilitates outgassing the metal during evacuation of the envelope. Outgassing metal parts in a vacuum device is always a serious problem, and is particularly difficult of accomplishment when a heavy piece of metal, such as iron core 24, is present. Our improved core, with its bore 26 communicating with the envelope, exposes the interior of the iron mass so that more thorough outgassing of the metal is assured.

Any suitable means, such as a high frequency coil disposed about the envelope, may be employed to heat the internal parts of the relay for outgassing purposes during the exhaust process.

We claim:

1. An electrical contactor device comprising an envelope having a pair of coaxial branches and a third branch angularly disposed thereto, a pair of aligned leads sealed in the coaxial branches, a third lead sealed in the third branch, an armature supported on the inner end of the third lead and engageable with either one or the other of the aligned leads, and a core carried by one of the aligned leads for controlling the armature.

2. An electrical contactor device comprising an envelope having a pair of coaxial branches and a third branch angularly disposed thereto, a pair of aligned leads sealed in the coaxial branches, a third lead sealed in the third branch, an armature supported on the inner end of the third lead and engageable with either one or the other of the aligned leads, a core carried by one of the aligned leads for controlling the armature, and resilient means for normally

holding the armature engaged with one of the aligned leads.

3. An electrical contactor device comprising an envelope having a pair of angularly disposed branches, leads sealed in said branches, an armature mounted on one and engageable with the other lead, a core in the branch containing said other lead, and a coil disposed about the last mentioned branch for magnetizing the core.

4. An electrical contactor device comprising an envelope having a pair of coaxial branches and a third branch angularly disposed thereto, a pair of aligned leads sealed in the coaxial branches, a third lead sealed in the third branch, an armature mounted on the third lead and engageable with either one or the other of the aligned leads, and a core carried by one of the aligned leads for controlling the armature, said core being supported on the lead at a point remote from the end of the branch in which the last mentioned lead is sealed.

5. An electrical contactor device comprising an envelope; a pair of leads projecting into the envelope; a magnetizable core carried by one of the leads; and an armature disposed between the leads comprising a pair of apertured plates, a sheet interposed between the plates, and a pair of contacts secured to opposite sides of the sheet and lying in the plate apertures.

6. An electrical contactor device comprising an evacuated envelope, a lead sealed in the envelope, another lead sealed in the envelope, an armature resiliently mounted on said other lead and engageable with the first mentioned lead, and a magnetizable core carried by the first mentioned lead.

7. An electrical contactor device comprising an evacuated envelope, a pair of leads sealed in the envelope, a third lead sealed in the envelope, an armature resiliently mounted on the third lead and engageable with either one or the other of said pair of leads, and a magnetizable core carried by one of said pair of leads.
